(57) **CLAIM**

The ornamental design for a magnetic pick-up tool, as shown and described.

DESCRIPTION

FIG. 1 is a front perspective view of the primary embodiment of the magnetic pick-up tool;

FIG. 2 is a front elevation of a first alternative embodiment of the finger gripping magnet extension mechanism;

FIG. 3 is a front elevation of the finger gripping magnetic extension mechanism of the primary embodiment of the magnetic pick-up tool;

FIG. 4 is a right side elevation view thereof;

FIG. 5 is a rear elevation view thereof;

FIG. 6 is a left side elevation view thereof;

FIG. 7 is a top plan view of the primary embodiment of the magnetic pick-up tool;

FIG. 8 is a bottom plan view thereof; and,

FIG. 9 is a vertical cross-sectional view taken along lines 9—9 of the thumb depressor member of the primary embodiment of the magnetic pick-up tool.

The finger gripping magnetic extension mechanism is shown separately in both embodiments for ease of illustration.
